Primary Examiner — Cynthia Ramirez*(74) Attorney, Agent, or Firm* — Grant's Law Firm; Allan Grant**CLAIM**

I claim the ornamental design for an engine test stand, as shown and as described.

DESCRIPTION

FIG. 1 is a perspective view of the engine test stand.

FIG. 2 is the front view of the engine test stand.

FIG. 3 is a back view of the engine test stand.

FIG. 4 is a side view of the engine test stand.

FIG. 5 is the other side view of the engine test stand.

FIG. 6 is a top view of the engine test stand.

FIG. 7 is bottom view of the engine test stand.

FIG. 8 is a perspective view of the engine test stand.

FIG. 9 is a perspective view of the engine test stand; and,

FIG. 10 is a perspective view of the engine test stand.

The wheels, engine, engine mount, battery, fuel can, oil can, fan, instrument panel and wiring shown in broken lines in the figures are to show environment and form no part of the claimed design.
